UNITED STATES PATENT OFFICE

SAMUEL SAMBOR, OF NEWARK, NEW JERSEY

WATER HEATER

Application filed June 9, 1927. Serial No. 197,664.

This invention relates to an improved hot water heater that is of small capacity but is adapted for supplying hot water quickly to a faucet at a minimum of expense in installation and in operation.

The invention comprises a heater casing with a coil of piping heated by a burner within it, the whole being supported adjacent to the faucet, the piping forming a by-pass around the valve of the faucet.

The invention is primarily designed for family use and is preferably constructed so that the heater casing and associated parts thereof are supported by the faucet.

15 The particular form of heater is adapted to be fed by a valve which is operated simultaneously with a valve of the gas burner of the heater, so that the water is started through the piping at the same time that the flame is increased and when the water supply is reduced the heat is likewise reduced.

The invention is illustrated in the accompanying drawings in which Figure 1 is a top view of a device embodying my invention. Figure 2 is a side view of the device shown in Figure 1 and Figure 3 is a front view thereof with the heater casing shown in section. Figure 4 is a section on line 4-4 in Figure 3.

20 In the drawing the faucet is indicated at 10 and has the usual valve operated by a handle 11, the faucet supplying cold water directly from the spout 12.

The heater casing is shown at 13, usually with perforated top and bottom caps 14 and at the inside is a burner 15 for heating the coils of piping 16 above it. This piping is connected by the length 17 to faucet in rear of the valve and by the length 18 to the faucet in front of the valve. It will be evident from this that water admitted to the piping while the burner is lighted will deliver hot water to the spout 12.

25 The inlet length 17 of the piping has a valve 19 for regulating the flow of water through it. The gas pipe 20 which supplies the burner 15 has a valve 21 for regulating the supply of gas. The valves are preferably operated together and for this purpose I show the handle 22 common to both valves

and placed so that when it is swung forward the water is turned into the piping and the gas is turned on to the burner and the water passing through the piping is thus instantly heated and delivered to the outlet of the faucet. A valve 23 can be placed in the reach 18 of the piping and can be equipped with a spout for hose attachment for rinsing dishes and the like instead of passing the water through the outlet 12. The parts of the heater are usually supported by passing the pipe 20 through a bracket or loop 24 on the faucet and a screw 25 is shown as a means for fastening the pipe 20.

30 A small pilot light may be placed in the burner in the usual manner.

I claim:—

1. A hot water heater comprising a faucet, a heater casing, a burner supporting the casing, the burner being supported on the faucet, piping in the casing and connected to the faucet in front and in rear of the faucet valve, a valve for the burner, a valve in the piping, and a handle for opening and closing these two valves simultaneously.

2. A hot water heater comprising a faucet, a heater casing, a gas burner in the casing, a rigid gas supply pipe connected to the burner, extended through the casing wall and supported by the faucet and thereby supporting the burner and the heater casing, a coil in the heater casing and connected to the faucet in front and in rear of the faucet valve, a valve in the connection in rear of the faucet valve, a valve in the gas pipe and in line with the valve in the connection, and a handle secured to both valves to operate them in unison.

In testimony whereof I affix my signature

SAMUEL SAMBOR.
